CLAIM

We claim the ornamental design for a stand up stapler, as shown and described.

DESCRIPTION

FIG. 1 is a right side perspective view of a stand up stapler showing our new design;

FIG. 2 is a right side elevational view showing our new design;

FIG. 3 is a left side elevational view showing our new design;

FIG. 4 is a top plan view showing our new design;

FIG. 5 is a bottom plan view showing our new design;

FIG. 6 is a front elevational view showing our new design; and,

FIG. 7 is a rear elevational view of showing our new design. The broken lines shown in FIGS. 5 and 7 represent unclaimed portions of the stand up stapler and form no part of the claimed design.
